BALL SHOOTING TOY

Claude W. Brimhall, Gaston, Ind.

Application January 2, 1946, Serial No. 638,696

3 Claims. (Cl. 46—43)

1

The invention aims to provide a novel, entertaining and durable toy for shooting marbles or other balls along a runway, by means of a rapid-fire, magazine-type, crank-actuated gun, and for returning the balls to the gun magazine for repeated firing as long as desired, with the intervals between shots either short or long, according to the speed with which the crank is turned.

The magazine preferably includes a hopper for the returned balls, and a further aim is to provide novel means for preventing overloading of said hopper and thereby preventing the balls from becoming wedged therein.

A still further object is to make novel provision for removing any of the balls which may fall back from a curved intermediate runway which connects a lower runway, along which the balls are shot, with an upper ball-returning runway.

Yet another object is to provide a novel construction which may be expeditiously manufactured primarily from wood, and may be profitably sold at a reasonable price.

Figure 1 is a side elevation.

Fig. 2 is a top plan view.

Fig. 3 is an enlarged fragmentary plan partly in horizontal section, as indicated by the irregular line 3—3 of Fig. 4.

Fig. 4 is an enlarged vertical longitudinal section on line 4—4 of Fig. 2 and Fig. 3.

Fig. 5 is a further enlarged detail longitudinal section on line 5—5 of Fig. 3.

Fig. 6 is a vertical transverse section on line 6—6 of Fig. 4.

Fig. 7 is a detail horizontal sectional view substantially on line 7—7 of Fig. 4.

Fig. 8 is a perspective view of one of the plunger and spring guides.

A preferred construction has been illustrated and will be rather specifically described, with the understanding, however, that within the scope of the invention as claimed, variations may be made.

A lower horizontal ball runway 10, an upper rearwardly declined ball-returning runway 11, and a curved runway 10' rigidly connecting the rear ends of said runways 10 and 11, are provided, and a rapid-fire, magazine-type, crank-actuated gun 12 is mounted on the rear end of the runway 10 under the rear end of the runway 11, for forwardly shooting balls 13 along the ball-guiding and returning runway formed jointly by the elements 10, 11 and 10', and for receiving the returned balls in readiness to be shot again. The shooting will occur repeatedly and almost continuously as long as the gun-actuating crank 14

is operated, and the intervals between shots may be controlled by turning said crank at one speed or another. The entire toy is preferably supported by legs 15 which space it sufficiently from the floor to make the crank 14 readily accessible to a child kneeling or sitting. The legs are preferably inwardly and upwardly foldable when the toy is to be stored.

The lower runway 10 comprises a bottom 16 and side strips 17 secured thereto by screws or the like 18, and the upper runway 11 likewise includes a bottom 19 and side strips 20 secured thereto by screws 21. The intermediate runway 10' comprises a curved plate 22 having integral side flanges 23. The lower end of this plate 22 is secured by bolts or the like 24 against the lower side of the runway bottom 16, at the front end of the latter, and the upper end of said plate 22 is spaced above the front end of the upper runway bottom 19. The lower ends of the flanges 23 are secured against the outer sides of the side strips 17 of the lower runway 10, by bolts or the like 25, and the upper ends of said flanges 23 are secured by bolts or the like 26 against the inner sides of the side strips 20 of the upper runway 11. Directly in front of the lower runway bottom 16, the plate 22 is provided with an integral channel-shaped portion 27 extending transversely thereof and slidably receiving a drawer 28 to collect any of the balls 13 which may fall back from the intermediate runway 10'. The bottom of the drawer 28 is formed with a ball outlet 29 and when said drawer is partly withdrawn from the channel 27 and tilted, any balls within said drawer will run to said outlet 29 and descend therethrough.

At the rear end of the upper runway 11, is a pivotally hung gate 30 which arrests the returned balls until they have accumulated against said gate in sufficient number to push the latter rearwardly to open position, whereupon the balls will drop into the magazine or hopper 31 of the gun 12, for gravitation to the ball shooting means hereinafter described. I have found that by thus arresting a number of the balls in the rear end of the runway 11, the presence of too many balls in the hopper or magazine 31 at one time, is prevented, thereby overcoming any tendency of the balls to wedge and lodge instead of properly gravitating to the shooting means. Immediately behind the gate 30, the side strips 20 of the upper runway 11, are secured to an end wall 32 by screws or the like.

The gun 12 includes two longitudinal side walls 33 preferably of greater height toward their

front ends than toward their rear ends, said side walls 33 being secured against the inner sides of the side strips 17 of the lower runway 10, by screws 34. The rear ends of these walls 33 are connected by a rear end wall 35. Extending from this end wall 35 to points somewhat in advance of the side walls 33, are a number of strips 36 which may be secured by nails or the like 37 upon the bottom 16 of the lower runway 10. In the present instance, there are three of the strips 36, two lying against the inner faces of the side walls 33 and one disposed centrally between said side walls.

A front end structure is secured by screws or the like 38 between the front ends of the side walls 33, said front end structure comprising a lower block 39 and an upper block 40 in the present showing, said lower block 39 having two vertical ball-guiding openings 41 between its ends. The upper block 40 inclines rearwardly from the upper side of the block 39 and its base is disposed totally in advance of the openings 41, and a suitable finishing plate 42 is preferably secured by screws or the like against the front areas of said blocks 39 and 40.

An intermediate transverse wall 43 is secured between the intermediate portions of the side walls 33, and a ball chute 44 rests upon the upper edge of this wall 43 and the rear portion of the block 39, said chute 44 being preferably removable to give access to mechanism below it for inspection and lubrication. The upper side of the chute 44 has appropriate ball-guiding ribs 45 to guide the balls 13 to the openings 41.

Spring - and - plunger - guiding, longitudinally split tubes 46 extend under the intermediate wall 43 and the rear end of the block 39 and abut the rear end wall 35. The front ends of these tubes 46 are held down by the block 39, and a horizontal plate 47 holds the rear portions of said tubes against ascent, said plate 47 being secured upon the rear portions of the strips 36 and coacting with the walls 33, 35 and 43 in forming a pocket in which to keep a number of the balls 13. Each tube 46 is provided between its ends with two spaced parallel longitudinal walls 48 which project upwardly and abut the block 39 and the wall 43 to thereby hold said tubes against longitudinal shifting. Lateral shifting of these tubes is prohibited by the strips 36 between which they are disposed.

Plungers 49 are slidable in the front portions of the tubes 46, each plunger being movable from a forward position (upper portion of Fig. 3 and Fig. 4) in which it directly supports the lowermost ball in one of the openings 41, to a rearward position (lower portion of Fig. 3 and Fig. 5) in which it allows the previously supported ball to drop to a shooting position in front of the plunger, in which position, the ball is yieldably held by a light transverse spring 50 suitably mounted at its ends on two of the strips 36, the upper edges of said strips being notched to receive said spring.

Plunger-projecting springs 51 are disposed in the rear end portions of the tubes 46 with their rear ends abutting a plate 52 suitably secured to the rear end wall 35. Forward movement of the plungers 49 is limited by stops 53 projecting upwardly from said plungers, said stops being cooperable with a stop plate 54 inset in and suitably secured upon the strips 36. Stops 53 may also project upwardly sufficiently to strike the rear end of the block 39.

Rotatably mounted in suitable openings in the

side walls 33, is a transverse shaft 55 which is provided with the crank 14 above described, said shaft being held against endwise movement in any suitable way. This shaft rigidly carries two tappet pins 56 cooperable with upstanding lugs 57 on the plungers 49 to retract and release said plungers as the shaft is rotated.

Whenever a plunger 49 occupies the forward position shown at the upper portion of Fig. 3 and in Fig. 4, it directly supports the lowermost of the balls 13 in one of the openings 41. When the plunger is withdrawn sufficiently by turning the crank 14, to clear the supported ball, this ball will drop to the shooting position shown at the lower portion of Fig. 3 and in Fig. 5, in which position it is yieldably held against displacement forwardly, by means of the spring 50. By the time the ball 13 reaches this shooting position or immediately thereafter, the plunger is released and its spring projects it forcibly forward, thus driving the ball under the spring 50 along the runway 10. The ball leaving this runway rolls along the curved runway 10' onto the upper runway 11 and returns along the latter. Rotation of the crank will successively shoot balls from "both barrels" of the gun and they may be shot in such rapid succession as to simulate real intensive machine-gun fire, or may be more slowly shot, simply by controlling the speed of the crank. When a sufficient number of balls collect against the gate 30, they push it open and descend into the hopper 31 in readiness for gravity-feed to the shooting means. The parts 58 are merely pivotally hung targets operable by the balls in the runway 11, and if desired, they may have scoring values, for use when using the toy to play a game.

From the foregoing, taken in connection with the accompanying drawings, it will be seen that a novel and advantageous provision has been made for carrying out the objects of the invention. While preferences have been disclosed, attention is again invited to the possibility of making variations within the scope of the invention as claimed. For example, the gun may be constructed in "single-barrel" form, instead of the "double-barrel" form shown.

I claim:

1. A ball shooting toy comprising a lower ball runway, a magazine type rapid-fire gun mounted at the rear end of said runway for shooting balls forwardly along said runway, said gun having a manually operated actuating crank the speed of which governs the intervals between shots, an upper ball runway disposed longitudinally above said lower runway, and a curved intermediate runway connecting the front ends of said lower and upper runways for directing the balls from said lower runway onto said upper runway when said balls are shot by said gun, the rear end of said upper runway being disposed at the magazine of said gun to return the balls to said magazine, said magazine including a hopper into which the balls are discharged from said ball runway, the delivery end of said runway being declined to said hopper and having a pressure-opened gate for arresting the entrance of balls into said hopper until said balls collect in sufficient number against said gate to push it open, thereby restricting the number of balls in said hopper to prevent them from wedging therein.

2. In a toy, a lower ball runway, a curved C-shaped runway connected with the front end of said lower runway to receive balls therefrom, the

lower front end of said curved runway being provided with a transverse upwardly open channel at the front end of said lower runway, and an upwardly open drawer in said channel to receive any balls which may fall rearwardly along said curved runway, said drawer being slid able at least partly from said channel for ball removal.

3. In a toy, a lower ball runway, a curved C-shaped runway connected with the front end of said lower runway to receive balls therefrom, the 10 lower front end of said curved runway being provided with a transverse upwardly open channel at the front end of said lower runway, and an upwardly open drawer in said channel to receive any balls which may fall rearwardly along said 15 curved runway, the bottom of said drawer having a ball outlet through which balls collected in said drawer may roll when said drawer is withdrawn sufficiently to move said ball outlet from the bottom of said channel.
